US00D488912S

(12) **United States Design Patent** (10) Patent No.: **US D488,912 S**
(45) Date of Patent: **** Apr. 27, 2004**

(54) **SEAT BELT POSITIONER**

FR	2674803	10/1992
JP	62-053268	3/1987
JP	04-146852	5/1992
WO	WO 93/21044	10/1993

(75) Inventor: **Russell Berger**, Needham, MA (US)

* cited by examiner

(73) Assignee: **Constance F. Berger**, Naples, FL (US)

Primary Examiner—Paula A. Mortimer

(**) Term: **14 Years**

(74) Attorney, Agent, or Firm—Barlow Josephs & Holmes, Ltd.

(21) Appl. No.: **29/178,796**(22) Filed: **Mar. 31, 2003**(57) **CLAIM**(51) LOC (7) Cl. **02-07**

The ornamental design for a seat belt positioner, as shown

(52) U.S. Cl. **D2/627**

and described.

(58) **Field of Search** D2/624, 627, 628,
D2/629, 640, 891; 24/200, 198, 265 AL,
315; 297/482, 466, 472, 484; 280/801.1;
2/300, 340, 231, 233**DESCRIPTION**(56) **References Cited**FIG. 1 is a perspective view of a seat belt positioner in an
opened unfolded condition showing my new design, the
dashed lines are conventional stitching;

FIG. 2 is a top view of thereof;

FIG. 3 is a bottom view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is an environmental view of the seat belt positioner
of FIG. 1 installed on a seat belt and folded over a should
belt for securing a passenger therein; the broken lines
forming no part of the present invention.**U.S. PATENT DOCUMENTS**
